to Universal Chain Co. Inc., Maplewood, N. J., a corporation of Rhode Island

Application June 8, 1953, Serial No. 25,385

Term of patent 7 years

(Cl. D45—16)

To all whom it may concern:

Be it known that I, Hermann Weinacker, a citizen of the United States of America, and a resident of Short Hills, county of Essex, and State of New Jersey, have invented a new, original, and ornamental Design for an Ornamental Chain, of which the following is a specification, reference being had to the accompanying drawing, forming a part thereof.

I claim:

The ornamental design for an ornamental chain, as shown.
